(57) **CLAIM**

The ornamental design for a pet habitat, as shown and described.

DESCRIPTION

FIG. 1 is a perspective view of a pet habitat showing one embodiment of my new design;

FIG. 2 is a rear elevation view thereof;

FIG. 3 is a left side elevation view thereof;

FIG. 4 is a right side elevation view thereof;

FIG. 5 is a front elevation view thereof;

FIG. 6 is a top plan view thereof;

FIG. 7 is a bottom plan view thereof;

FIG. 8 is a perspective view of a pet habitat showing another embodiment of my new design;

FIG. 9 is a rear elevation view thereof;

FIG. 10 is a front elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken line showing of holes in FIGS. 8–14 are for illustrative purposes only and form no part of the claimed design.
